UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 12, 1922. Serial No. 581,470.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Apparatus, of which the following is a specification.

10 My invention relates to railway traffic controlling systems, and particularly to systems of the type wherein cab signals or speed governing apparatus, located on the railway train, are controlled by current supplied to the train from the trackway.

I will describe several forms of apparatus embodying my invention, and will then point out the novel features thereof in claims.

20 In the accompanying drawings, Fig. 1 is a perspective view showing a track, a train thereon, and certain parts of one form of apparatus embodying my invention. Fig. 2 is a view, partly diagrammatic and partly in section, showing one form of train-carried apparatus embodying my invention. Fig. 3 is a diagrammatic view illustrating in simplified form the electrical connections of the apparatus shown in Fig. 2. Fig. 4 is a group of curves illustrating the characteristics of the currents in certain parts of the apparatus shown in Figs. 2 and 3. Fig. 5 is a view showing a modification of the apparatus shown in Fig. 2. Fig. 6 is a 35 diagrammatic view showing one form of trackway apparatus embodying my invention.

Similar reference characters refer to similar parts in each of the several views.

40 Referring first to Fig. 1, the reference characters 2 and 2^a, designate the track rails of a railway, and V designates a vehicle, such as a car or train, traveling on the rails 2 and 2^a in the direction indicated by the arrow 5. The vehicle V, which I will hereinafter term a train, comprises a forward axle 3 provided with a pair of wheels 4, 4, and another axle 3^a provided with a pair of wheels 4^a, 4^a. Surrounding the forward 45 axle 3 are two magnetizable cores 7 and 8. The track rails 2 and 2^a are supplied with direct current from a trackway battery 11, which battery is connected with these rails

through a pole-changer 12 and wires 13 and 14. It will be seen from the structure illustrated in Fig. 1 that when the pole-changer 12 is in one position, direct current will flow through the forward axle 3 in the direction indicated by the arrows 6, whereas when the pole-changer 12 is reversed, direct current will flow through the axle 3 in the direction opposite to that indicated by the arrows 6. This direct current, of course, flows through the two cores 7 and 8.

The magnetizable core 7 surrounding axle 3 is provided with two coils 9 and 9^a as shown in Fig. 2, whereas the core 8 is provided with two similar coils 10 and 10^a. These coils are constantly supplied with alternating current from a generator 25 and the frequency of this current I will herein assume to be 25 cycles per second. Generator 25 is constantly driven by a suitable prime mover on the train V, such for example as a direct current motor 15 supplied with energy from a storage battery 16.

The two coils 9 and 10 are connected in series in a circuit which passes from the generator 25, through wires 17 and 18, coil 9, wires 19 and 20, coil 10, and wires 21, 22, 23 to the generator 25. The other coils 9^a and 10^a are also included in series in a circuit which passes from generator 25, through wires 17, 24 and 29, coil 10^a, wires 26 and 27, coil 9^a, and wires 28 and 23 to generator 25. These circuits are so arranged that the magnetomotive forces created in each core 7 and 8 by the two coils thereon are in the same direction, whereas the currents induced in the axle 3 by the magnetomotive forces in the two cores 7 and 8 oppose each other.

The train is provided with a relay D which, as here shown, is of the induction motor type, comprising a rotor 60 and two stator windings 34 and 35. One terminal of winding 34 is connected through wire 32 with the point 30 between the two coils 9 and 10, whereas the other terminal of the relay winding 34 is connected through wire 33 with the point 31 between the two coils 9^a and 10^a. The other stator winding 35 of relay D is connected through wires 36 and 37 with an alternating current generator 50 which is constantly driven by the motor 15 and the frequency of which generator I

will assume to be 50 cycles per second, that is, twice the frequency of the generator 25. Referring now to Fig. 3, it will be seen that the arrangement of the coils on the cores 7 and 8, the generator 25, and the relay winding 34, constitutes a Wheatstone bridge, the four legs of which are the coils 9, 10, 9^a and 10^a, the relay winding 34 being the bridge member of the bridge. When there is no direct current in the axle 3 of Figs. 1 and 2, the bridge is balanced so that no voltage is applied to the terminals of relay winding 34, and, consequently, no current flows in this winding. If, due to some defect, the balance between the four coils is disturbed, alternating current of 25 cycles will flow through the relay winding 34, but the relay will not be energized because its other winding 35 is supplied with 50 cycle current and this relay can operate only when both windings are supplied with currents of the same frequency. If direct current flows through the axle 3, however, it will produce a magnetic bias and distort the wave form of the alternating currents or voltages in the four coils carried by the cores 7 and 8, this bias at any instant producing an effect upon the two coils carried on core 7 opposite to that produced upon the two coils carried on core 8. The resultant change in wave form from a sine wave is illustrated in Fig. 4, from which it will be seen that at any given instant if the alternating current in the coils on core 7 is increased, the alternating current in the coils on core 8 will be decreased. The result of this is that the current in coil 9 will be greater than that in coil 10, and the current in coil 9^a will be greater than that in coil 10^a, and, referring to Fig. 3, an equalizing current will flow from point 30, through the relay winding 34 to point 31. One-half cycle later the current through the bridge arms will obviously be in the opposite direction, and the currents in coils 10 and 10^a will be greater than those in coils 9 and 9^a, so that the equalizing current will then flow from point 30, through relay winding 34 to point 31, as before. This equalizing current is, therefore, in the same direction when the alternating current is a positive maximum and when it is a negative maximum, and hence it is of double the frequency of the generator 25, that is, the equalizing current is of 50 cycles per second. Fifty cycle current is then supplied to both of the stator windings of relay D, so that this relay will be energized in one direction or the other. The double frequency current supplied to relay winding 34 is a measure of the direct current through the axle 3. Reversing the polarity of the direct current through the axle, reverses the relative polarity of the double frequency current, and so the relay

D will be energized in one direction or the other depending upon the direction in which the direct current flows through axle 3.

The apparatus interposed between the 25 cycle generator and the relay winding 34 70 may be termed a static frequency doubler.

Referring now to Fig. 2, the relay D may be employed to control any suitable signal or apparatus of other form on the train. As shown in this view, the train is equipped 75 with the signal S^v, and with speed control apparatus comprising a high speed magnet H and a medium speed magnet M. The signal S^v includes three electric lamps G, Y and R, adapted when lighted to indicate 80 respectively "proceed," "caution" and "stop." The speed controlling apparatus including the magnets H and M may be of any suitable or desired type, but inasmuch as this apparatus has nothing to do with 85 the present invention it is omitted from the drawings.

When direct current of what I will term normal polarity is supplied to the axle 3, relay D will be energized in what I will 90 term normal direction, so that its contact 38-39 is closed. The proceed lamp G of signal S is then illuminated through a circuit which passes from generator 25, through wires 23, 22, and 42, relay contact 95 38-39, wire 43, proceed lamp G, and wires 44, 49, 24 and 17, to generator 25. At the same time the high speed magnet H is energized through wire 47. When direct current of reverse polarity is supplied to the 100 axle 3, relay D is energized in reverse direction so that its contact 38-40 is closed, whereupon the caution lamp Y is lighted through this contact of the relay and wire 45; the medium speed magnet M is also 105 energized through contact 38-40, and wires 45 and 48. When the supply of direct current to the axle 3 is discontinued, relay D becomes de-energized so that its back contact 38-41 is closed, whereupon the stop lamp 110 R is lighted through this contact and wire 46; both of the magnets H and M are then de-energized.

Referring now to Fig. 5, the apparatus shown in this view is the same as that shown 115 in Fig. 2, except that an electron tube amplifying device E is interposed between the frequency doubler and the relay winding 34. This amplifying device which, as here shown, is of the electron tube type, comprises a filament 55, a grid 56, and a plate 57, all enclosed in a vacuum tube 61. The filament 55 is constantly heated by a battery 58. The primary 52 of a transformer 51 is connected across the points 30 and 31, 120 and a condenser 53 is included in series with the primary 52, this primary circuit being preferably tuned to resonance at 50 cycles per second. The secondary 54 of transformer 51 is connected across the fila- 130

ment and grid of electron tube E, whereas the relay winding 34 is included in a plate circuit for this tube, which circuit includes a battery 59. It will be seen, therefore, that 5 a comparatively feeble alternating difference of potential across the points 30 and 31 will cause variations of considerably greater amplitude in the current supplied to relay winding 34 by the battery 59. The apparatus shown in Fig. 5 may be preferable to that shown in Fig. 2 when low values of track circuit current are employed, such as current supplied by the usual track batteries in a direct current signaling system. 10 Referring now to Fig. 6, the reference characters 2 and 2^a designate the track rails of a railway along which traffic normally moves in the direction indicated by the arrow. These rails are divided by insulated 15 joints 82 into a plurality of blocks of which only one block A—C is shown in the drawing, it being understood that each block is equipped with apparatus similar to that which is provided for block A—C. This 20 block is sub-divided into a rear section A—B and a forward section B—C. The rear section A—B is provided with a track relay T', which is connected across the rails adjacent the entrance end of the 25 section. The forward section B—C is provided with two track relays T² and T³ connected across the rails adjacent the entrance and exit ends of the section respectively. The supply of track circuit current to the 30 rails of the rear section is controlled by a line relay L', which relay in turn is controlled by both track relays T² and T³ for the forward section and is supplied with current of normal or reverse polarity, de- 35 pending on the condition of track relay T' for the block next in advance of block A—C. When relay T' is closed, that is, when there is no train in the block in advance of A—C, the circuit for line relay L' passes from the upper terminal of a bat- 40 tery 62, through the front point of contact 63 of track relay T', contact 64 of track relay T³, contact 65 of track relay T², winding of relay L', and thence through a com- 45 mon return conductor O (not shown in full) to the middle point of battery 62. The current which is then supplied to line relay L' is of normal polarity. When track relay T' is open, that is, when the block 50 immediately to the right of point C is oc- cupied by a train, the circuit for line relay L' is from the lower terminal of bat- 55 tery 62, through the back point of contact 63 of track relay T', and then as before 60 to the middle point of battery 62. Current of reverse polarity is then supplied to line relay L'. Line relay L' includes two polarized contacts 67 and 68 which consti- 65 tute a pole-changer for connecting a bat- 70 tery 66 in one direction or the other across the track rails of the rear section A—B, this connection also including neutral contacts 69 and 70, so that when relay L' is open, due to the presence of a train in the advance section B—C, the supply of cur- 75 rent to the rails of section A—B is discontinued. Current of normal or reverse polarity is supplied to the rails of section A—B from battery 66 according as relay L' is energized with current of normal or re- 80 verse polarity from battery 62. The advance section B—C is provided with two track batteries 73 and 74, located adjacent the entrance and the exit ends of this section, respectively. When track re- 85 lay T' is closed, track battery 74 is connected across the rails at the exit end of the section B—C through contact 75 of this relay, but when this relay is open battery 74 is disconnected from the rails. When track relay T' is open, a line relay L² is energized through the back point of contact 71 of this track relay, and battery 73 is then connected across the rails of section B—C at the entrance end of this section 90 through contact 72 of relay L². It will be seen, therefore, that battery 73 or battery 74 is connected with the rails of section B—C as track relay T' for the next section to the right is open or closed. Both track 95 relays T² and T³ are closed by either battery 73 or 74. The operation of the apparatus shown in Fig. 6 is as follows: 100 Assuming that the block to the right of block A—C is unoccupied, a train equipped with the apparatus shown in Fig. 2 or Fig. 5 entering block A—C will receive current of normal polarity from battery 66 as long as the train occupies the rear section A—B, 105 and so a proceed indication will be given on the train. As the train passes into the advance section B—C it will receive track circuit current of normal polarity from battery 74 and so the proceed indication will 110 still be given on the train. If the block to the right of block A—C is occupied, however, track relay T' will be open so that line relay L' will be reversed and current of reverse polarity will then be supplied to 115 the rails of the rear section A—B from battery 66. Under this condition a train passing through block A—C will receive a caution indication throughout the rear section A—B. Track battery 74 will now be dis- 120 connected from the rails and track battery 73 will be connected to the rails, so that as the train enters section B—C, its forward axle 3 will be shunted or cut off from battery 73 by axle 3^a and it will receive no current from the track rails, and, conse- 125 quently, a stop indication will be given on the train. While the train is in section B—C, track relays T² and T³ will both be open, so that line relay L' will be de-ener- 130

gized with the result that battery 66 is disconnected from the rails of the rear section A—B, so that a following train entering this section will receive a stop indication.

5 As shown in Fig. 6, the block A—C is provided with a signal S^A, which is located adjacent the entrance end of the block, and the block to the right of block A—C is provided with a similar signal S^C. Signal S^A is controlled by track relay T' and by a line relay F^A, which line relay in turn is controlled by a polarized contact 76 in line relay L'. Relay F^A is closed when line relay L' is energized in normal direction but 10 not when line relay L' is energized in reverse direction or is de-energized. Signal S^A is provided with a caution indication circuit which passes from terminal B of a suitable source of current through the front 15 point of contact 77 of track relay T', wire 78, and operating mechanism of signal S^A to terminal O of the same source of current. This signal is further provided with a proceed indication circuit including contact 20 77 of track relay T', wire 79, contact 80 of line relay F^A, and wire 81. It will be seen from the foregoing that when block A—C and the block next to the right are unoccupied, relay L' is energized in normal direction, so that line relay F^A is closed 25 and signal S^A consequently indicates proceed. When the block to the right of A—C is occupied, line relay L' is energized in reverse direction, so that line relay F^A is open 30 and signal S^A then indicates caution, assuming, of course, that block A—C is unoccupied. When block A—C is occupied, track relay T' is open, so that signal S^A then indicates stop. It will be noted that 35 track relay T' is open when either section of block A—C is occupied; that is, when a train is in section A—B the supply of current to track relay T' is shunted by the wheels and axles of such train, whereas, 40 when the train is in section B—C track relays T² and T³ are both open, so that line relay L' is open and the supply of current to section A—B is then discontinued by the contacts 69 and 70 of relay L'.

45 50 Although I have herein shown and described only certain forms of apparatus embodying my invention, it is understood that various changes and modifications may be made therein within the scope of the appended claims without departing from the spirit and scope of my invention.

Having thus described my invention, what I claim is:

1. In combination, a railway vehicle, two 55 magnetizable cores on an axle thereof, two coils on each core, a circuit on said vehicle including a first source of alternating current and two multiple branches each including in series one coil on each core, a relay 60 on said vehicle having a winding controlled

by the difference of potential between a point in said first branch between the two coils therein and a point in said second branch between the two coils therein, said relay including a second winding supplied 70 with alternating current from a vehicle carried source having twice the frequency of the first source, vehicle governing apparatus controlled by said relay, and means located in the trackway for passing direct current 75 through said vehicle axle.

2. In combination, a railway vehicle, two magnetizable cores on an axle thereof, two coils on each core, a circuit on said vehicle including a first source of alternating current and two multiple branches each including in series one coil on each core, said coils being so connected that at any given instant the fluxes produced by the two coils on each core are in the same direction but 80 the electromotive forces produced in said axle by said two cores oppose each other, a relay on said vehicle having a winding controlled by the difference of potential between a point in said first branch between 85 the two coils therein and a point in said second branch between the two coils therein, said relay including a second winding supplied with alternating current from a vehicle carried source having twice the 90 frequency of the first source, vehicle governing apparatus controlled by said relay, and means located in the trackway for passing direct current through said vehicle axle.

3. In combination, a railway vehicle, two 95 magnetizable cores on an axle thereof, two coils on each core, a circuit on said vehicle including a first source of alternating current and two multiple branches each including in series one coil on each core, a relay 100 on said vehicle having a winding, controlled by the difference of potential between a point in said first branch between the two coils therein and a point in said second branch between the two coils therein, said relay including a second winding supplied with alternating current from a vehicle carried source having twice the frequency of the first source, vehicle governing apparatus controlled by said relay, and means located in the trackway for passing direct current 105 through said vehicle axle.

4. In combination, a railway vehicle, two magnetizable cores on an axle thereof, two 110 coils on each core, a circuit on said vehicle including a first source of alternating current and two multiple branches each including in series one coil on each core, a relay 115 on said vehicle having a winding controlled by the difference of potential between a point in said first branch between the two coils therein and a point in said second branch between the two coils therein, said relay including a second winding supplied 120 with alternating current from a vehicle carried source having twice the frequency of the first source, vehicle governing apparatus controlled by said relay, and means located in the trackway for passing direct current through said vehicle axle in one direction or the other.

4. In combination, a railway vehicle, two magnetizable cores on an axle thereof, two 125 coils on each core, a circuit on said vehicle including a first source of alternating current and two multiple branches each including in series one coil on each core, a relay on said vehicle having a winding controlled by the difference of potential between a point in said first branch between the two coils therein and a point in said second branch between the two coils therein, said relay including a second winding supplied 130

- with alternating current from a vehicle carried source having twice the frequency of the first source, vehicle governing apparatus controlled by said relay, and means located 5 in the trackway and controlled by traffic conditions in advance for passing direct current through said vehicle axle in one direction under clear traffic conditions and in the opposite direction under caution traffic conditions. 10
5. In combination, a railway vehicle, two magnetizable cores on an axle thereof, two coils on each core, a circuit on said vehicle including a first source of alternating current and two multiple branches each including in series one coil on each core, a relay on said vehicle having a winding controlled by the difference of potential between a point in said first branch between the two 20 coils therein and a point in said second branch between the two coils therein, said relay including a second winding supplied with alternating current from a vehicle carried source having twice the frequency of the first source, vehicle governing apparatus controlled by said relay, and means located in the trackway and controlled by traffic conditions in advance for passing direct current through said vehicle axle. 25
6. In combination, a railway vehicle, two magnetizable cores on an axle thereof, two coils on each core, a circuit on said vehicle including a first source of alternating current and two multiple branches each including in series one coil on each core, amplifying means on the vehicle having an input circuit controlled by the potential difference between two points in said two branches respectively each point being between the two coils in the branch, a relay on the vehicle having two windings one of which is supplied with current by the output circuit of said amplifying means, said relay including a second winding supplied 40 with alternating current from a vehicle carried source having twice the frequency of the first source, vehicle governing apparatus controlled by said relay, and means located in the trackway for passing direct current through said vehicle axle. 45
7. In combination, a railway vehicle, two sources of alternating current thereon differing in frequency, a relay having two windings associated respectively with said two sources, trackway means for changing the frequency of the current from one of said sources to the frequency of the other source, and governing means on the vehicle controlled by said relay. 50
8. In combination, a railway vehicle, two sources of alternating current thereon differing in frequency, a relay having two windings associated respectively with said two sources, means interposed between one of said sources and the associated relay winding and responsive to the presence of direct current for changing the frequency delivered to such winding to the frequency of the other source, trackway means for supplying direct current to said frequency 70 charging means, and governing means on said vehicle controlled by said relay. 75
9. In combination, a railway vehicle, two sources of alternating current thereon differing in frequency, means located partly on the vehicle and partly in the trackway for supplying a receiving circuit with current from one of said sources modified into the frequency of the other source, and governing means on the vehicle controlled by 80 said receiving circuit and by the other source. 85
10. In combination, a stretch of railway track divided into blocks each comprising a rear and a forward section; and means for supplying direct current of normal polarity to the rails of both sections of a block at the exit end thereof when the block next in advance is clear, and for discontinuing the supply of direct current from the exit 90 end of the forward section and supplying direct current of reverse polarity to the rear section when the block next in advance is occupied. 95
11. In combination, a stretch of railway track divided into blocks each having a rear and a forward section, a track relay connected with the rails of each rear section, at the entrance end thereof, two track relays connected with the rails of each forward section at the entrance and exit ends respectively, a line relay for each rear section controlled by the track relays for the associated forward section and supplied with current of normal or reverse polarity according as 105 the first track relay for the next block in advance is closed or open, means for supplying the rails of each rear section with direct current of normal or reverse polarity according as the associated line relay is energized in normal or reverse direction and for discontinuing the supply of current when such relay is open, means for supplying direct current of normal polarity to the rails of each forward section at the exit end 110 when the block next in advance is unoccupied but not when it is occupied, and means for supplying direct current to the rails of each forward section at the entrance end thereof when the block next in advance is 115 occupied. 120
12. In combination, a railway vehicle, a static frequency doubler thereon, a source of alternating current on the vehicle for said frequency doubler, means located in the trackway for supplying direct current to said frequency doubler, and governing means on said vehicle controlled by said doubler. 125
13. In combination, a railway vehicle, a

first source of alternating current thereon, a static frequency doubler on said vehicle supplied with current from said first source, a second source of alternating current on 5 said vehicle the frequency of which is twice that of said first source, trackway means for supplying direct current to said frequency doubler, and governing means on said vehicle controlled jointly by said frequency doubler and by said second source of alternating current.

14. In combination, a railway vehicle, a first source of alternating current thereon, a static frequency doubler on said vehicle supplied with current from said first source, 15 a second source of alternating current on said vehicle the frequency of which is twice that of said first source, trackway means for supplying direct current to said frequency

doubler, a relay on said vehicle having two 20 windings one of which is supplied with current from said frequency doubler and the other with current from said second source, and governing means on said vehicle controlled by said relay.

15. In combination, a railway vehicle, a static frequency doubler thereon, a source of alternating current on the vehicle for said frequency doubler, means located in the trackway for supplying direct current to 30 said frequency doubler, governing means on said vehicle controlled by said frequency doubler, and amplifying means interposed between said doubler and said governing means.

In testimony whereof I affix my signature.

LLOYD V. LEWIS.
